UNITED STATES PATENT OFFICE.

CARRIE E. SCHUETZE, OF DETROIT, MICHIGAN.

DESIGN FOR A COMBINATION BIRD CAGE AND SUPPORT.

Application filed February 14, 1925. Serial No. 12,382. Term of patent 7 years.

To all whom it may concern:

Be it known that I, CARRIE E. SCHUETZE, a citizen of the United States, residing at Detroit, county of Wayne, State of Michigan, have invented a new, original, and ornamental Design for Combination Bird Cage and Support, of which the following is a specification, reference being had to the accompanying drawing, forming part thereof, and in which:

Figure 1 is a front elevation of the new design of combination bird cage and support; and,

Figure 2 is a perspective view showing the reverse side of Figure 1.

I claim:

The ornamental design for a combination bird cage and support, as shown.

CARRIE E. SCHUETZE.
